UNITED STATES PATENT OFFICE

2,555,136

TIE PRESS FORM

Victor C. J. Kaiser, Indianapolis, Ind.

Application November 7, 1947, Serial No. 784,653

1 Claim. (Cl. 223—82)

1

This invention relates to a tie press form.

The principal object of the present invention is to provide a tie press form of great simplicity and consisting of a semi-rigid elongated metal body with a water absorbent material cover coextensively secured thereto by a waterproof heat-resisting adhesive.

The chief feature of the present invention resides in the semi-rigid, slightly flexible non-absorbent body having at least one side coextensively secured to a water-absorbing fibrous cover.

Other features of the invention will be set forth more fully and become apparent from the following description and claim:

The full nature of the invention will be understood from the accompanying drawings and the following description and claim:

In the drawings.

Figure 1 is a perspective view of the tie press form, a portion being broken away to show parts in greater detail.

Figure 2 is a longitudinal sectional view showing the position of the waterproof heat-resisting adhesive and absorbent material cover in relationship to the metal body.

Figure 3 is a transverse sectional view showing the invention in operation.

In the drawing there is shown a tie press form comprising a non-absorbent semi-rigid and slightly resilient tapered sheet metal body 10, of suitable thickness. 11 indicates a water absorbent material cover having raw edges coextensively secured upon the body by a waterproof heat-resisting adhesive layer. 12 indicates a hole for hanging or storing said tie press form when not in use. The absorbent material cover 11 may be a fabric sheet or a flocculent material, such as cotton linters.

If the cover 11 is a fabric sheet, it is secured to the metal body 10 as by spraying at least one side of said body 10 with a coating of waterproof heat-resisting adhesive 13. The fabric cover sheet may be placed upon the sprayed metal body 10 and then rolled down until all wrinkles have been eliminated and the surface is smooth.

If the cover 11 is a flocculent material it is secured to the metal body 10 as by spraying at least one side of said body 10 with a coating of waterproof heat-resisting adhesive 13. The floc is then blown on or otherwise applied to the adhesive-coated surface and to the desired thickness.

The invention as described herein is so constructed that there can be no cracking or breaking in use. Warping also is impossible. The cover 11 also will not wrinkle. The durability of this tie press form is unlimited whereas a

2

tie press of fiber base material of the desired thickness proves unsuccessful for it will absorb water and warp and/or crack and/or break.

Reference will now be had to Figure 3 showing the invention in operation. The absorbent material cover 11 is dampened with a sponge; then the small end of the tie press form is slipped into the open end of the tie material 14 adjacent the lining 15 until the sides of the tie are firmly engaged by the form.

The tie and the press form are placed on a board, table, or cabinet, and a hot iron 16 is passed over the tie material 14, thus transferring the heat through the tie material 14. This softens the tie material to eliminate all wrinkles. The iron 16 when passed over the tie dries and presses it. The form is then removed.

From the foregoing description it is readily seen that due to the simplicity of construction and operation anyone can use the tie press form; also the non-wrinkle proof cover combined with the thin non-breakable or non-warping body enables the user to attain maximum speed of application and use. It has been demonstrated that ties can be pressed at the rate of one a minute for several hours if necessary.

While the invention has been illustrated and described in great detail in the drawings and foregoing description, the same is to be considered as illustrative and not restrictive in character.

The invention claimed is:

An elongated tie press form having a tapered outline adapted to fit within the end of a necktie, said form comprising a base of relatively thin semi-rigid and slightly resilient sheet metal, and a relatively thin water absorbent fibrous cover having raw edges and being formed to dimensions coextensive with those of one face of said base, said cover being secured to said one face by a waterproof heat resisting adhesive.

VICTOR C. J. KAISER.
